FLUID INLET-OUTLET DEVICE, PARTICULARLY FOR CLINICAL PURPOSES

Raymond M. Curtis, Baltimore, Md., assignor to Macalaster Bicknell Company, Cambridge, Mass., a corporation of Massachusetts

Application April 5, 1943, Serial No. 481,828

1 Claim. (Cl. 128—214)

1 My present invention relates to the preparation and administering of fluids for medical, surgical, laboratory, hospital and like purposes, and especially in connection with the administration of blood and blood plasma. More particularly it aims to provide a simple device or unit adapted to serve at times as a fluid inlet for a container and at other times as an outlet and relief vent, making it unnecessary to install separate devices for the different functions.

In the drawing illustrating by way of example on embodiment of the invention:

Fig. 1 is an elevation of the needle-like unit as a whole;

Fig. 2 shows the same in longitudinal section;

Fig. 3 is a cross-section as on the line 3—3 of Fig. 1, enlarged;

Fig. 4 illustrates one use of the device, as an inlet;

Fig. 5 correspondingly shows the same needle unit serving as an outlet and vent for the same container;

Fig. 6 is an elevation similar to Fig. 1 of a modified form of compound needle embodying the invention;

Fig. 7 is an enlarged section on the line 7—7 of Fig. 6; and

Fig. 8 is a section similar to Fig. 7 representing a further embodiment.

Referring first to Figs. 1 to 3, the plural-purpose unit comprises a first and relatively long needle-like tube or tubular piercing needle member 6 having at one end a sharp beveled point 7 which may be similar to that of a hypodermic needle. Its opposite end is equipped with a nipple 8 for attaching a rubber or other flexible tubing.

The unit further includes a second and relatively shorter tube or hollow needle member 9, also having a point 10 at one end, preferably beveled similarly to that of the longer member 6, and being equipped with a tubing-receiving nipple 11 at its other end. These needle members are formed of a rigid non-corrosive material, preferably a stainless steel.

The two needle members are disposed in close parallelism, with their corresponding ends toward the same end of the device as a whole but with the point 10 of the shorter member 9 set back substantially from that of the longer member 6. The extent of the latter beyond the pointed end of the shorter needle member may be variously proportioned, depending mainly on the type and size of container with which the device is to be used. The two needle members

or tubes 6 and 9 are securely interattached in the described position by a union or connection preferably having a cross-sectional area but little exceeding that of the combined members themselves. As here shown the connecting means comprises a sleeve 12 which desirably also is of stainless steel or other non-corrosive material such as that of the needle members themselves, or said means may consist of a welded or other union of the contacting portions of the needle tubes.

The described connecting means preferably includes a laterally projecting disk-like flange 13 integrally or otherwise related and itself serving as a further union for the two needle members. This member 13 acts also as a finger piece or guard and at times as a stop, in a manner to be referred to later.

Beyond this guard and finger piece 13 the main tubular needle-like members 6 and 9 are relatively deflected from each other into a Y-formation or the like. One of the members may be straight or substantially so, the other being bent at an angle of 45° or thereabouts, or both members may be deflected to an extent to give the desired separation of their end portions 8 and 11. As here illustrated, for example, the shorter member 9 is straight or substantially so while the longer member 6 has its tube-receiving end 8 bent outwardly.

The needle-like combined inlet and outlet device of the invention is susceptible of various uses. By way of example I have in Figs. 4 and 5 illustrated it in connection with the technique of re-converting dehydrated blood plasma to a solution and administering the same.

In these figures, referring first more particularly to Fig. 4, is shown a container C suitable for the storage of dehydrated blood plasma P, usually a glass jar. According to one method, the desiccated plasma P is kept in the container under a negative pressure (partial vacuum) maintained by a sealing closure S. At least a central portion of the closure as at S' is formed of a puncturable material such as a relatively soft rubber or like composition. When the dried plasma is to be administered, it is first restored to liquid form as by the addition of sterile water.

For this purpose my needle unit has its longer member 6 thrust through the pierceable area S' of the closure sufficiently to project its pointed end 7 below the seal S, but leaving the pointed end 10 of the shorter needle member 9 outside the container. An appropriate length of rubber or other flexible hose or tubing t is affixed to the

nipped end 8 of the inserted needle member 6, the tubing being placed in communication with the sterile water supply. The water automatically flows into the container, by reason of the partial vacuum therein. The tubing is clamped off or removed from the supply when the appropriate quantity of water has been received in the container to place the plasma in solution at the desired concentration. The dried plasma content is of such measured quantity that the resulting solution leaves some free space within the container.

The procedure for administering the liquid plasma to a patient is represented in connection with Fig. 5. Following the admission of water as in Fig. 4, the tubing *t* is removed from the longer needle member 6. The needle unit as a whole is then forced further through the penetrable portion S' of the closure, so as to present the pointed end 10 of the shorter and herein straight needle member 9 within the container and below the closure S—S'.

The operator readily accomplishes this by engaging with his fingers the finger-piece and guard 13 and thrusting downwardly against it, thus avoiding contact with the tube-receiving portions of either needle member, particularly that of the member 9 which now is to serve as the outlet for the plasma solution. This manipulating flange or finger-piece 13 at the same time serves also as a limiting stop, bringing up flatwise against the outer face of the closure S—S' and so determining the appropriate maximum entry of the needle device into the container.

A length of tubing *t*' has one end installed over the attaching nipple 11 of the needle member 9, and has at its other end the usual venipuncturing needle for insertion into a vein of the patient, the tubing generally also being equipped with any suitable shut-off or clamp device, not shown, and desirable also with an adequate filter.

With the needle unit thrust fully home into the position substantially as shown in Fig. 5, the tubing *t*' with administering needle being attached, the container C is inverted and suspended conveniently adjacent the patient, as by any suitable hanger means R. The initial upper level of the solution or plasma fluid F is indicated by the broken line in Fig. 5 adjacent the bottom wall of the container C, which wall is now uppermost. As previously explained, the fluid content is such as to leave some free space, and the length of the longer needle member 6, beyond the stop element 13, is so proportioned to the size and shape of the container C that the open pointed end of this needle member 6 now projects upwardly into the free space, above the level F. The nipple end 8 outside the container is open to atmosphere, through a sterile air strainer if desired, so that the needle member 6 now functions as a relief vent, relieving any partial vacuum within the container and permitting the fluid plasma content to flow by gravity to the patient.

It will be understood that the needle unit of the invention is equally useful in instances where the dried plasma is not vacuum packed, the water or solution fluid being supplied through tubing *t* similarly as in Fig. 4, by gravity or under pressure. Whichever needle member is not then used as the inlet is adapted to serve as a relief vent, the unit as a whole being inserted through the closure such as S—S' far enough to clear the pointed end 10 of the shorter member below the closure. Thus under some circumstances either

member 6 or 9 may be utilized as the inlet, the other serving as a relief vent. Also, in the vacuum technique as above described in connection with Fig. 4, if the vacuum should fail, the inflow of the solution fluid usually can be continued by inserting the needle unit sufficiently further, beyond the position shown in Fig. 4, to enable the shorter needle member 9 to serve as a vent. Other fluids than blood and liquid plasma also may be handled through the medium of the plural-function needle device of the present invention in the general manner as above explained.

Referring now to Figs. 6 and 7, the plural needle unit as there shown comprises a first and relatively longer needle member 16 which may in general be substantially the same as the member 6 of Figs. 1 to 5, including a piercing point 17 at one end and a tubing attaching formation 18 at the other end. In this instance this longer or main needle member 16 is substantially straight throughout and extends at its tube-receiving end 18 beyond the corresponding end of the other and parallel needle member 19.

Noting also Fig. 7, the needle member 16 has formed along an intermediate portion a groove or longitudinal depression 16a. The second and relatively shorter needle member, in this case of substantially smaller gauge than the first member 16, is set into and secured in this groove, as by brazing, welding or otherwise. This second needle or venting member as shown has a pointed or other open end as at 20 and a nipped or otherwise apertured end, preferably offset from the needle member 16, as at 21. The end 20 of this shorter needle member 16 is so positioned relative to the adjacent end of the groove or slot 16a of the other member as to provide an opening or vent as at 16b, said end 20 as well as substantially the entire straight or parallel portion of this shorter member 16 being in effect sheathed in, or within the periphery of, the main needle member 16.

As in the device of Figs. 1 to 5 the needle unit desirably has fixed on it a lateral flange, stop or guard and finger piece 23, although in some instances this may be dispensed with. Also, under circumstances where the sheathed tubular member or needle 16 is to be employed mainly or only as a venting means its laterally deflected portion or the nipped or like end thereof may be omitted. It will also be understood similarly as in connection with Figs. 1 to 5, that the relative extent of the two members 16 and 19 at their non-piercing ends may be substantially equal or may be reversed or otherwise than as shown, and that either, both or neither may be laterally bent or deflected.

In Fig. 8, I have illustrated another structural form which otherwise than as stated may be the same as in Figs. 6 and 7. In this instance, however, the smaller and generally shorter member 29 is wholly surrounded by the tubular wall of the main needle member 26, the latter being laterally apertured at the appropriate spaced points for communication therethrough with the opposite ends of the member 29. Said contained member 29 is fixed in position in any convenient manner as by interengagement of either or both ends with the adjacent aperturing formation of the needle member 26, or by brazing, welding or otherwise interattaching the two members.

It will be seen that in the embodiments as shown in Figs. 6, 7 and 8 by way of example the needle unit as a whole has in effect a common piercing point 17 and that the shorter members

19 and 29 are wholly or substantially within the outer circumferential compass of the needle member 16 which carries such piercing point. Thus the units of Figs. 6 and 7 and of Fig. 8 are adapted for use with containers and the like wherein the puncturable or inserting area of the closure or needle-receiving formation is relatively limited. For convenience in identification the parallel tubular or needle-like members, both with respect to Figs. 1 to 5 and the other figures, may be referred to as having inner ends, as 7, 10, 17 and 20 and outer ends, as 8, 11, 18 and 21.

It also will be understood that the accompanying drawing is not to scale and that for the sake of clearness in illustration various dimensions, particularly wall thicknesses and internal diameters are exaggerated. Merely by way of example, the stainless steel or other needle members such as 6 and 9 of Figs. 1 to 5 and 16 or 26 of Figs. 6 to 8 may be of approximately 12 gauge, while the partly or wholly enclosed members such as 19 and 29 of the latter figures may have a gauge of about 15 or smaller.

My invention is not limited to the particular embodiments thereof as herein illustrated and described, its scope being pointed out in the following claim.

I claim:

A dual clinical needle of non-corrosive metal such as stainless steel, for piercing self-sealing insertion through a puncturable closure of a container, said needle comprising a pair of generally parallel tubes of unequal length having their channels closely contiguous and each of uniform diameter throughout, said tubes constructed and arranged for use interchangeably one as a vent and the other as an inlet or as an outlet respectively to admit fluid to an upright closed container or to withdraw fluid from such container in an inverted position, particularly in the transfer of blood and blood plasma, said tubes being

open at both ends, tubing attaching formations at one end of each tube, said ends being disposed at a divergent angle to each other and terminating at adjacent transverse planes at the outer end of the needle as a whole, the opposite or inserting end of the longer tube having a bevelled and sharpened open point for piercing insertion of the needle in sealing relation through puncturable closure element of a container and the proximate inserting end of the shorter tube being shaped and disposed for entry through the closure element following penetration thereof by the longer tube and being set back from the pointed end of said longer tube to an extent permitting the shorter tube to be positioned wholly outside a container while the longer tube has its pointed end projected into such container through and substantially beyond the closure element thereof for sealed inflow of fluid to the container, means interattaching the tubes along their contiguous portions from the inserting end of the shorter to their point of divergence adjacent their tubing attaching ends, and a laterally projecting disk-like flange surrounding and secured to an interattached portion of the tubes spaced closer to said point of divergence than to the inserting end of the shorter tube, both tubes being of such relatively small cross-sectional diameter and having their axes so contiguously disposed along their interattached portions that their interaxial distance is less or not appreciably greater than one-half their combined outer diameters, the longer tube having an external longitudinal seating recess corresponding in length to that of the shorter tube and the latter being in substantial part received and secured in said recess, and whereby their interattached portions are adapted for penetrative passage as a unit through the puncturable container closure element.
